NIPPERS OR SIMILAR TOOL.

1,163,733.

Specification of Letters Patent.

Patented Dec. 14, 1915.

Application filed April 22, 1913. Serial No. 762,873.

To all whom it may concern:

Be it known that I, WILLIAM A. BERNARD, a citizen of the United States, residing in New Haven, county of New Haven, and 5 State of Connecticut, have invented certain new and useful Improvements in Nippers or Similar Tools, of which the following is a full, clear, and exact description.

This invention relates primarily to tools 10 for nipping, or cutting off, the ends of nails or brads which protrude from the upper or inner surfaces of boot and shoe soles.

The objects of the invention are to provide a tool of such shape and construction 15 that easy access may be had to objectionable nails, regardless of their location relatively to the inner face of the shoe sole; to provide a construction whereby the protruding nail may be cut off cleanly at a point flush with 20 the sole surface; to furnish a tool in which a very powerful leverage may be exerted on the nipper edges, whereby the nails may be sheared off with great facility; and to improve the general construction and operation 25 of nippers, for the purposes above mentioned and analogous purposes.

To these and other ends, the invention consists in the novel features and combinations of parts to be hereinafter described 30 and claimed.

In the accompanying drawing, Figure 1 is a face elevation of a tool embodying my improvements, looking toward that face which is uppermost when the tool is introduced into a boot or shoe for the purpose mentioned, the jaws being in the normal open position; Fig. 2 is an opposite or bottom face view with the jaws closed; Fig. 3 is a lateral edge view of Fig. 1; Fig. 4 is a 40 front end elevation of Fig. 2; and Fig. 5 is an enlarged detail section on line 5—5 of Fig. 3.

Referring to the drawing, 6 and 7 denote sheet metal handle levers of closed cross- 45 sectional form. These handle levers are pivoted together intermediate of the ends of the same by means of a pivot pin 8. Those portions 6^a and 7^a respectively of the handle levers which are disposed in front of the 50 pivot 8 are quite short as compared to the rear portions of the levers which are intended to be grasped by the hand of the operator. In the form shown, the pivot pin 8 passes through lugs or ears 9 on the member 6, which are located outside of and in

alinement with coöperating ears 10 formed on the member 7. The forward extremity of the portion 6^a is pivoted by means of a pin 11 to the shank 12 of a jaw 13, and the portion 7^a is pivoted in a similar manner 60 by means of a pin 14 to the shank 15 of a jaw 16. The jaws 13 and 16 are pivoted together intermediate of their ends by means of a pivot pin 17, the shanks 12 and 15 being disposed at the rear of said pivot pin, and 65 the jaws being provided in front of the pivot pin 17 with coöperating cutting edges 18 and 19.

The forward extremities of the portions 6^a and 7^a are left open to accommodate the 70 rear extremities of the shanks 12 and 15, and the pins 11 and 14, as shown in Fig. 5. The jaws 13 and 16 are preferably of solid or cast construction, and the pivotal connection between said jaws is effected by providing the jaw 12 with a pair of lugs 20, 75 between which is interposed a similar lug 21 of the jaw 16. The pivot pin 17 passes through all three of these lugs, and is preferably smoothed off flush with the respective 80 faces of the jaws.

The cutting edges 18, 19 are disposed lengthwise of the jaws, the operating portions of the latter being cut away as shown in Fig. 1 to present edges substantially flush 85 with the lower surfaces of the jaws, as shown in Fig. 2. These edges are disposed approximately at right angles to the axis of the pivot 17, thereby providing what is known in the art as a "side cutter". 90

By referring to Fig. 3, it will be noted that the jaws 13, 16 are gently curved substantially throughout their length, and that the handle members 6 and 7 are curved 95 to form a continuation of the jaw curve. In other words, the tool as a whole is curved longitudinally in such a manner that the upper face thereof presents a generally concave shape, whereas the lower surface presents a corresponding convex shape. As a 100 result the tool may be inserted in a boot or shoe in such a manner that when the cutting edges 18, 19 lie against and approximately parallel to the inner surface of the sole the handles 6 and 7 will project up out 105 of the boot or shoe at the heel portion thereof, so that the handle members may be readily manipulated to operate the cutter. In other words, the tool is curved substantially throughout its length on a curve disposed in 110

a plane perpendicular to the plane of operation of the cutting edges. The cutting edges are located at the same side of the tool as the convex portion of the curved handle levers. The operation of the tool in cutting nails out of shoes is also facilitated by making the tool quite narrow throughout the greater part of its length, as shown, so that the jaws 13, 16 may be introduced into small shoes without difficulty. The cutting edges or blades 18, 19 will be the only portions of the tool to contact with the sole surface, and the lower faces of the jaws 13, 16 will preferably be finished off smoothly, so as not to catch on the shoe sole. As previously stated, the pivot pin 17 does not project beyond the lower surface of the jaws where it would interfere with the operation thereof.

The parts are normally held in the position indicated in Fig. 1 of the drawings, the cutting portions of the jaws being in open position, with the shanks 12 and 15 in contact in substantially parallel relation, and the portions 6^a and 7^a positioned close together in parallel relation. This is effected by a coil spring 22 embracing the main pivot 8 within the handle members 6, 7, and having its opposite end portions 22^a, 22^b abutted against the outer walls of the respective handle members. Injury of the cutting edges by forcing them together with excessive pressure is prevented by a stop screw 23 passing through the shank of one of the handle members (such as 6) at a point in the rear of the main pivot, and adapted to contact with the opposing portion of the other handle member.

The operation of the improved tool will be obvious, for the most part, from the foregoing description. The jaws 13, 16 may be readily introduced into the shoe or boot so as to reach the protruding nail, even if the latter is located in the extreme toe portion of the shoe or boot. When the cutting edges have straddled the nail at a point substantially flush with the inner surface of the shoe sole, said edges are brought together

by operation of the handle members 6, 7 in an obvious manner. As the shanks 12, 15 50 of the cutting jaws are longer than the cutting portions of said jaws a very powerful compound leverage is provided, and as a result the cutting edges will shear off nails very readily and quickly with the application of but a comparatively slight force to the handle members. 55

The connection between the jaws and the handle members is preferably a detachable one to provide for the repair and replacement of the jaws. In the form shown, the pins 11 and 14 are headed at one end, and are provided with nuts 11^a and 14^a respectively at the opposite end. By removing the nuts 11^a, 14^a, the jaws may be readily detached. In some cases, it may be desirable to use different kinds of jaws with the same pair of handle levers. 60 65

While the foregoing description is necessarily a detailed one in so far as it concerns 70 the particular embodiment of my invention selected for illustration, it will be understood that various modifications of the construction may be adopted within the scope of the claim. 75

What I claim is:

A pair of nippers for cutting pegs in shoes consisting of two substantially flat pivotally united cutting jaws, normally separated, upwardly curved shanks extending rearwardly from the jaws and normally held in contact in substantially parallel relation, and handle parts pivotally united adjacent to their lower ends, the lower parts thereof being normally positioned close together in 80 parallel relation and pivotally connected to the rear ends of the shanks, the handles being curved upwardly throughout the length thereof. 85

In witness whereof, I have hereunto set 90 my hand on the 21st day of April, 1913.

WILLIAM A. BERNARD.
